UNITED STATES PATENT OFFICE.

CHARLES J. FRANKS, OF CINCINNATI, OHIO, ASSIGNOR TO CHARLES WEIGEL, OF CINCINNATI, OHIO.

CRATE FOR CARRYING BOTTLES.

1,049,295.

Specification of Letters Patent.

Patented Dec. 31, 1912.

Application filed August 21, 1911. Serial No. 645,162.

To all whom it may concern:

Be it known that I, CHARLES J. FRANKS, a citizen of the United States, residing at the city of Cincinnati, in the county of 5 Hamilton and State of Ohio, have invented certain new and useful Improvements in Crates for Carrying Bottles, of which the following is a specification.

The object of my invention is to produce 10 a cheap, simple, and efficient metal crate or box to be used in carrying and conveying bottles.

One of the features of my invention is to produce a box having two or more runners 15 stamped in the bottom of the crate, and extending therefrom, so that the crate will ride on the boxes or crates packed around it when it is moved in or out of its position.

Another feature consists in forming the 20 bottom separate and connecting it to the body by rivets.

Another feature consists in turning the strengthening or brace wires at top edge of 25 crate, and at the handles inward so the crate at its outside will present a smooth uninterrupted surface, enabling it to slide against its companion boxes without jar or interruption.

Another feature consists in a novel and 30 unique method of connecting the bottle carrying tray to the crate body.

The box is preferably made completely of sheet metal.

In the accompanying drawings forming 35 part of this specification, Figure 1 is an isometric view of my new crate; Fig. 2 is a longitudinal section taken on lines 2—2 of Fig. 1; Fig. 3 is a cross-section taken on line 3—3 of Fig. 1; and Fig. 4 is a section 40 taken on line 4—4 of Fig. 1.

In the present instance the crate is rectangular in form, consisting of sides 1, 1, and ends 2, 2, the ends having hand-holes 3. Strengthening or brace wires 4 are placed 45 at the top edge of the crate, and at the hand-holes, the metal of the crate being rolled

over said wires 4 on the inside of the crate, so that a smooth outside surface will result.

The bottom 5 of the crate is pressed up in pan shape having sides and ends 6, which 50 are riveted to the body of the crate by rivets 7. Into the bottom 5 are pressed the runners 8, 8, shaped as shown and inclined at their ends, and provided with vent holes 9. These holes 9 allow any water or moisture 55 which might accumulate in bottom of the crate to run off. The bottom 5 is also provided, between the runners 8, 8, with holes 10. These holes are present for ventilation and for allowing waste water, liquid or dirt 60 to pass out of the crate in order to keep it in a sanitary condition. They also allow ice water to surround the bottles when the whole crate filled with bottles is placed in a cooler or refrigerator. 65

The partitions, bottle supporters and holders are marked 12, 14. They are connected to the walls of the crate as follows: In the walls of the crate at suitable intervals I pinch cleats as 15; these cleats are 70 slipped through slots 16 in the frames of the bottle holding partitions 12 and 14 (see Fig. 4). The partitions 12 and 14 are bent over at their ends 17 and stepped as shown in said Fig. 4, so that when the cleats 15 75 are clamped or crimped into holding or locking position, they are raised, as shown in said Fig. 4, the unstepped portion 18 of the end 17 covering the hole left by the cleats 15. By this construction a smooth 80 surface is left on the walls of the outside of the crate, and the lock is rigid and permanent for the bottle holding partitions. The runners can be made of any size, shape, contour or of any number. I may stamp the 85 crate and bottom in one piece if I desire.

It will readily be observed that my new crate will work with great efficiency among its companion crates, as the runners holding it off the boxes above and below, will allow 90 it to slide, and being smooth will allow it to pass without undue impingement, render-

ing it possible to handle the crate very quickly.

I may make the crate out of any other material than metal if I find it practical to do so.

What I claim as new and of my invention, and desire to secure by Letters Patent is:

In a crate of the character described, a body portion, a bottom, runners stamped

into the bottom and integral therewith, said 10 runners tapered at their ends, vent holes provided in said runners, the body portion and bottom stamped separately and riveted together, as set forth.

CHARLES J. FRANKS.

Witnesses:

CHARLES WEIGEL,
JOHN W. STREHLI.
